UNITED STATES PATENT OFFICE.

GERHARD IMMUND AND CARL JANSSEN, OF ESSEN, GERMANY, ASSIGNEES TO FRIED.
KRUPP AKTIENGESELLSCHAFT, OF ESSEN-ON-THE-RUHR, GERMANY.

SELF-DISCHARGING CAR.

Application filed July 13, 1928, Serial No. 292,521, and in Germany December 1, 1927.

The invention relates to self-discharging cars of the type in which a member effecting the discharge of the car is in connection with the underframe by a lever and link gear which is actuated by a compressed air gear. The object of the invention is a discharging gear of this type which is of a particularly simple construction.

In order to allow of the invention to be more easily understood, an embodiment of same is diagrammatically illustrated by way of example in the drawing which accompanies and forms part of this specification.

In this drawing

Figure 1 is an end view of the self-discharging car in loading position, and

Figure 2 is a corresponding view in discharging position.

The box A of the self-discharging car is tippingly mounted on the underframe B by means of supports provided on the latter and having tipping bearings b^1 , and has a discharging door a^1 . The latter is in a known manner connected with the underframe B by a system of levers a^2 , a^3 . A link and lever system a^4 b^2 is interposed between the box A itself and the underframe B, the lever b^2 being rigid on a shaft b^3 mounted on the underframe B. The shaft b^3 further carries a lever b^4 connected thereto by a coupling means (not shown), e. g. a toothed coupling. The latter is designed so as to enable the lever b^4 to freely rock a certain angle about the shaft b^3 before the latter takes part in this rocking motion. A catch b^5 is rigid on lever b^4 and adapted to engage a pin a^5 laterally projecting from link a^4 of the system a^4 b^2 , Figure 1. A compressed air cylinder C is swingingly mounted on the underframe, the piston rod c^1 of which cylinder is guided by means of a roller c^2 in a slotted bracket D preferably mounted on the box A, and is further connected to lever b^4 by a link E.

In the loading position the parts described assume the position illustrated in Figure 1, in which the system a^4 b^2 is in or nearly in one dead position and secured therein by the catch b^5 of lever b^4 engaging the pin a^5 of the link a^4 . When the car should be dis-

charged, compressed air is supplied to the cylinder C. The piston rod c^1 then first shifts within the slotted bracket D and rocks the lever b^4 by means of link E, lever b^4 first rocking freely on shaft b^3 . When this takes place, the catch b^5 releases the pin a^5 of link a^4 . At the end of this motion lever b^4 engages shaft b^3 and rocks the system a^4 b^2 out of dead position, this system thereupon tipping the box A into discharging position. When the car should be moved back to loading position, the air supply to the gear C c^1 is reversed, whereupon the system a^4 b^2 and therewith box A is returned to initial position by piston rod c^1 and link E connected thereto. Toward the end of this motion, in which the box A together with the system a^4 b^2 leads with regard to the system E b^4 under the action of the weight of the door a^1 that closes itself, also the catch b^5 re-engages the pin a^5 and locks the discharging gear.

What we claim is:

1. In a self-discharging car an underframe, a tipping part and a compressed air gear mounted on said underframe, a lever fulcrumed on said underframe, a link connecting said lever to said tipping part, another lever fulcrumed on said underframe, another link connecting said last-named lever to the piston rod of said gear, a bolt rigid on said last-named lever and adapted to lock said first-named link in the loading position of said tipping part, and means for coupling with one another said two levers at a determined moment after said gear has come to act.

2. In a self-discharging car an underframe, a tipping part and a compressed air gear swingingly mounted on said underframe, a lever fulcrumed on said underframe, a link connecting said lever to said tipping part, another lever fulcrumed on said underframe, another link connecting said last-named lever to the piston rod of said gear, a bolt rigid on said last-named lever and adapted to lock said first-named link in the loading position of said tipping part, means for coupling with one another said two levers at a determined moment after

said gear has come to act, and a slotted bracket mounted on said tipping part and adapted to guide the piston rod of said gear.

3. In a self-discharging car an underframe, a tipping part and a compressed air gear mounted on said underframe, a lever fulcrumed on said underframe, a link connecting said lever to said tipping part, another lever fulcrumed on said underframe co-axially to said first-named lever, another link connecting said last-named lever to the piston rod of said gear, a bolt rigid on said last-named lever and adapted to lock said first-named link in the loading position of said tipping part, and means for coupling with one another said two levers at a determined moment after said gear has come to act.

The foregoing specification signed at Cologne, Germany, this 22 day of June, 1925.

GERHARD IMMUND.
CARL JANSSEN.
